UNITED STATES PATENT OFFICE.

FRANKLIN H. SPICER, OF WASHINGTON, DISTRICT OF COLUMBIA.

HOLDER FOR OIL-CANS.

SPECIFICATION forming part of Letters Patent No. 785,054, dated March 14, 1905.

Application filed November 15, 1904. Serial No. 233,128.

To all whom it may concern:

Be it known that I, FRANKLIN H. SPICER, a citizen of the United States, and a resident of Washington, in the District of Columbia, have 5 made a certain new and useful Invention in Holders for Oil-Cans; and I declare the following to be a full, clear, and exact description of the same, such as will enable others skilled in the art to which it appertains to make and 10 use the invention, reference being had to the accompanying drawings, and to letters of reference marked thereon, which form a part of this specification.

Figure 1 is a side view showing the invention. Fig. 2 is a side view showing the can open and its spout in pendent position. Fig. 3 is a perspective view of the holder.

The invention relates to devices for holding small oil-cans, such as are designed for use 20 in connection with sewing-machines and for other purposes; and it consists in the novel construction and combinations of parts, as hereinafter set forth.

In the accompanying drawings the letter *a* 25 designates such an oil-can having the usual small tapering spout *b*, which is attached to the neck of the body of the can by a screw connection. When the spout is detached for the purpose of filling the can, it is apt to be 30 laid down anywhere, and in this way may easily soil some delicate fabric, or it may be mislaid, causing loss of time. The oil-can itself usually becomes more or less coated with oil, so that it is not in condition to be placed upon 35 a shelf or table, especially when fine work is being done upon clean fabrics.

To obviate the difficulty of disposing of the can, the invention consists of the holding attachment *c*, which is made of wire and has, 40 in connection with the main portion *d*, which receives the body of the can, an arm *e*, pivotally connected or hinged to said main portion and provided with a loop-bearing *m*, adapted to receive the spout of the can, the latter being 45 engaged therewith near the screw-connection end.

In the construction shown the base or main portion *d* of the holder consists of a piece of wire bent in form to provide the base-bars *g*,

on which the bottom of the can rests, and the 50 loop-lugs *h*, which are turned upward and inward to engage the rim of the can-base and hold it in place. The wire base is also provided with a loop at one side, as at *k*, to which is connected the end loop of the pendent wire 55 arm *t*. This wire arm has a stem portion *s* and a transverse branch *v* at the end of said stem portion, said transverse branch having a circular bearing or ring *m* at its end. The angular portion at the junction of the stem 60 and branch forms a loop, whereby the holder and the can therein can be hung to a tack or small nail or to a hook under the table of the sewing-machine or in other convenient place. The bearing-ring *m* is designed to be placed 65 on the spout of the can, and the stem of the arm *t* is made a little longer than height of the body of the can, so that when the spout is secured to the can the loop will engage the spout a little above the screw portion. The 70 loop or ring bearing *m* is usually not closed, but is left with a free end, so that it will engage the spout with some elastic pressure, thereby holding it in a sufficiently secure manner to prevent casual disengagement. At the 75 same time the engagement is sufficiently free to permit the spout to be readily turned and manipulated in unscrewing it from the can-body or in screwing it thereto.

The holder attachment is light and affords 80 a means for holding the can without touching it with the fingers, as it is designed to remain upon the can at all times. When the can is to be filled, the spout is unscrewed and allowed to drop, and the pivoted arm of the holder 85 will fall in pendent position, holding the spout inverted, so that any oil that may adhere to the screw end will not be liable to come in contact with anything. The spout can be readily raised to position for attachment and 90 screwed to the neck of the can without disengaging it from the pivoted arm.

Having described the invention, what I claim, and desire to secure by Letters Patent, 95 is—

1. An oil-can holder adapted to be attached to the base of a can, and provided with a pivoted arm having a loop-bearing for connection

with the spout of the can, substantially as specified.

2. An oil-can holder consisting of a wire base having attachment-lugs, and a pendent arm pivoted thereto having a loop-bearing for the spout of the can, substantially as specified.

In testimony whereof I affix my signature in presence of two witnesses.

FRANKLIN H. SPICER.
